CLAIM

The ornamental design for a collator for an electrographic apparatus, substantially as shown and described.

DESCRIPTION

FIG. 1 is a top, left side and rear perspective view of a collator showing our new design;

FIG. 2 is a top right side and rear perspective view thereof;

FIG. 3 is a top, left side and front perspective view of a second embodiment of the design shown in FIG. 1;

FIG. 4 is a top, right side and rear perspective view thereof;

FIG. 5 is a right side elevational view thereof;

FIG. 6 is a left side elevational view thereof;

FIG. 7 is a front elevational view thereof; and,

FIG. 8 is a top plan view thereof.

The bottom view of the design is conventionally plain and substantially unornamented.

FIG. 1

FIG. 2

FIG. 3**FIG. 4**

FIG. 5

FIG. 6

FIG. 7

FIG. 8

UNITED STATES PATENT AND TRADEMARK OFFICE
CERTIFICATE OF CORRECTION

PATENT NO. : D245,166

DATED : July 26, 1977

INVENTOR(S) : Ernest Michael Bevilacqua, Allen Dana Hawthorne
Eliot Fette Noyes

It is certified that error appears in the above-identified patent and that said Letters Patent are hereby corrected as shown below:

In the Claim, "electrographic" should be --electrophotographic--.

Signed and Sealed this

Fifteenth Day of November 1977
